(57) **CLAIM**

I claim, the ornamental design for a trunk, as shown and described.

DESCRIPTION

FIG. 1 is a perspective view of a trunk, showing my new design in first embodiment;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective bottom view thereof;

FIG. 9 is a perspective view of a trunk, showing my new design in a second embodiment;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is a perspective bottom view thereof;

FIG. 17 is a perspective view of a trunk, showing my new design in a third embodiment;

FIG. 18 is a front view thereof;

FIG. 19 is a rear view thereof;

FIG. 20 is a left side view thereof;

FIG. 21 is a right side view thereof;

FIG. 22 is a top view thereof;

FIG. 23 is a bottom view thereof;

FIG. 24 is a perspective bottom view thereof;

FIG. 25 is a perspective view of a trunk, showing my new design in a fourth embodiment;

FIG. 26 is a front view thereof;

FIG. 27 is a rear view thereof;

FIG. 28 is a left side view thereof;

FIG. 29 is a right side view thereof;

FIG. 30 is a top view thereof;

FIG. 31 is a bottom view thereof; and,

FIG. 32 is a perspective bottom view thereof.

The broken lines illustrate portions of the trunk and form no part of the claimed design.

1 Claim, 32 Drawing Sheets
